C. O. Shepherd Attorney

UNITED STATES PATENT OFFICE.

WILLIAM E. ROSEL, OF COLUMBUS, OHIO.

DESIGN FOR A SPARK-PLUG TOOL.

53,641.

Specification for Design.

Patented July 22, 1919.

Application filed April 10, 1919. Serial No. 289,141. Term of patent 14 years.

To all whom it may concern:

Be it known that I, WILLIAM E. ROSEL, a citizen of the United States, residing at Columbus, in the county of Franklin and State of Ohio, have invented a new, original, and ornamental Design for a Spark-Plug Tool, of which the following is a specification, reference being had to the accompanying drawing, forming part thereof.

The figure is a perspective view of a spark plug tool, showing my new design.

I claim:

The ornamental design for a spark plug tool, as shown.

WILLIAM E. ROSEL.
